UNITED STATES PATENT OFFICE.

IKLEY C. FIFE, OF TOLEDO, OHIO.

GARMENT-FASTENER.

1,360,385.

Specification of Letters Patent. Patented Nov. 30, 1920.

Application filed April 21, 1920. Serial No. 375,496.

To all whom it may concern:

Be it known that I, IKLEY C. FIFE, a citizen of the United States, residing at Toledo, in the county of Lucas and State 5 of Ohio, have invented certain new and useful Improvements in Garment-Fasteners, of which the following is a specification.

This invention relates to garment fasteners and more particularly to an improved type of fastener for holding the meeting edges of a garment in releasably fixed relation.

The primary object of the invention is to 10 provide a garment fastener which will include pin members adapted to be thrust through portions of the garment to provide means whereby a releasable clip may be utilized to hold the meeting edges of the 20 garment together.

Other objects of the invention will appear upon consideration of the following detailed description and accompanying drawing, wherein:—

25 Figure 1 is a side elevation of a portion of a garment showing two meeting edges thereof and the application of the invention thereto.

Fig. 2 is an elevation of the opposite side 30 of the device.

Fig. 3 is a section on the line 3—3 of Fig. 1.

Fig. 4 is a section on the line 4—4 of Fig. 2.

35 Fig. 5 is a perspective view of the pin member and

Fig. 6 is a perspective view of the clip member.

Referring to the drawings by numerals the 40 sections of the material A and B indicate the meeting edges which are to be connected together in close proximity. Each of the portions A and B having longitudinally extended therethrough the pin member 45 shown in detail in Fig. 5 and which consists of the straight shank 1 having a loop 2 formed at one end by bending the end of the shank into the form of a ring thus providing a stop member. The opposite end 50 of the shank of the pin member is bent upon itself and the bent portion is sharpened to provide a pin point 3 whereby the pin may be thrust through the material. From the point 3 the two converging portions 55 4 extend which are gradually separated to provide a tapered end whereby the point

may conveniently pass through the material and the portions 4 are then bent toward each other as indicated at 5 forming a loop 6 for the reception of a ring 7. The ring 60 may be removed or inserted by permitting the two sections 4 to spring outwardly away from each other.

Before inserting the pin member, the ring is disconnected and the points are thrust 65 through the material at a point indicated at 8 and then extended along one side of the material for any desired length whereupon the pin is again thrust through the material at the point indicated at 9. The 70 two straight portions 10 at one side of the material are therefore provided and when the rings 7 are placed in position it will be obvious that the pin member cannot be accidentally or casually removed.

The clip member shown in Fig. 6 consists of a loop 11 adapted to receive one of the members 10 and the clip also includes the overlapped end sections 12 and 13, the section 12 being adapted to be sprung 80 inwardly whereby the loop 14 at the opposite end of the clip member may receive the other complementary section 10 of the pin member. Obviously both of the members may be readily connected and disconnected with the clip member to retain or release the meeting edges of the material as desired.

Minor changes in the details of construction may be made without departing from 90 the spirit of the invention or the scope of the claims hereunto appended.

What I claim is:—

1. A garment fastener comprising complementary pin members adapted to be 95 mounted on the meeting edges of the garment and each comprising a straight shank portion having one end provided with a loop and the opposite end provided with a pointed member forming a loop, a removable ring carried by the loop in the pointed end of the pin member, and a removable clip adapted to engage the shank portions of the pin members.

2. A garment fastener comprising a pair 105 of complementary pin members each including a straight shank having one end provided with a loop and the opposite end provided with a pointed section, said pointed section having a sharpened point and 110 diverging portions forming a loop, releasable rings carried in the loop at the point-

ed end of each pin member, and a spring clip member having a loop at each end adapted to be releasably connected with each of the straight portions of the pin members.

3. A garment fastener including a pair of pin members each consisting of a straight shank portion having a circular stop member formed at one end and a pointed section formed at the opposite end, the pointed section comprising a sharpened bent portion, the bent-portion forming opposite

diverging members shaped to extend toward each other at points spaced from the said sharpened end of the pointed member to 15 form a loop, and a releasable ring adapted for reception in the loop.

In testimony whereof, I have affixed my signature in the presence of two witnesses.

IKLEY C. FIFE.
